CLAIM

The ornamental design for energy module design, as shown.

DESCRIPTION

FIG. 1 is a perspective view of an energy module design according to an embodiment of the present invention;

FIG. 2 is a perspective view thereof;

FIG. 3 is a top plan view thereof;

FIG. 4 is a front elevational view thereof;

FIG. 5 is a right side elevational view thereof, the left side elevational view is a mirror image of the right side;

FIG. 6 is a back elevational view thereof;

FIG. 7 is a bottom plan view thereof;

FIG. 8 is a perspective view of an energy module design according to another embodiment of the present invention;

FIG. 9 is a perspective view thereof;

FIG. 10 is a top plan view thereof;

FIG. 11 is a front elevational view thereof;

FIG. 12 is a right side elevational view thereof, the left side elevational view is a mirror image of the right side;

FIG. 13 is a back elevational view thereof; and,

FIG. 14 is a bottom plan view thereof.
